BOX FORMING MACHINE

George T. Hart, Lynn, and Malcolm Seymour,
Cohasset, Mass., assignors to United Shoe Ma-
chinery Corporation, Flemington, N. J., a cor-
poration of New Jersey

Application March 9, 1945, Serial No. 581,794

2 Claims. (Cl. 93—49)

1

This invention relates to semiautomatic machines for forming the ends of paper boxes presented thereto by an operator, and more particularly to machines for forming blanks precoated with an adhesive, then dry, which is activated in the machine itself.

In the forming of paper boxes, the adhesive is commonly applied immediately prior to the folding of the box blank, and that folding takes place while the adhesive is still wet and tacky. If satisfactory production is to be attained, it is necessary that the adhesive on the box end shall set promptly and, to accomplish this with the commonly used adhesives such as animal or vegetable glues, it is necessary to apply extreme pressures so that the liquid, usually water, which is contained in the glue may be absorbed by the blank. The pressures employed are of the order of 200 to 400 pounds per square inch, thus involving in the case of shoe boxes a total pressure of 4,800 to 9,600 pounds per end. It will be obvious, therefore, that very rugged machinery is required, thus making it difficult to provide a simple, inexpensive machine which may be employed when it is desired to form the boxes at the place where they are to be used rather than at a box-making plant. Many advantages, prominent among which are savings in shipping and storage, accrue when it is possible to set the boxes up at the time and place where they are used. Such a procedure, however, involves difficulties not only because of the ruggedness of the required machinery but also because of the variations in the adhesives usually employed.

Furthermore, such water-soluble adhesives as animal and vegetable glues, dextrose and the like, commonly are subject to deterioration by reason of the development of bacteria, partly because of their origin, and the employees who handle such machines for relatively small quantities of boxes are not skilled in the handling and treatment of adhesives. When the blank can be precoated before shipment and this coating operation carried out at a box-making plant where conditions are controlled and where skilled operatives are employed, some of these difficulties disappear. With ordinary adhesives, however, the tackiness of the coated blanks even after the adhesive has been dried prohibits such a procedure, and even latex adhesives which are not subject to many of the disadvantages noted above are sufficiently tacky so that the coated blanks cannot be stacked because of the pressure-sensitive quality which is inherent in that type of adhesive.

On the other hand, it is possible to precoat

blanks with a thermoplastic adhesive which will dry quickly and which, when dry, is not tacky, thus permitting the blanks to be readily handled and stacked. Pressure-sensitive adhesives, however, and water-soluble adhesives cannot be stacked without danger that they will stick together and become "blocked." Many thermoplastic adhesives can be activated by passing a high-frequency electrostatic field through them.

Accordingly, an important object of our invention is to provide an improved and relatively inexpensive box-end-forming apparatus which is suitable for use in plants, such as shoe factories, for example, where the boxes are to be filled.

15 In accordance with a feature of the invention, box-end-forming instrumentalities arranged for the successive presentation to them of the end portions of a partially folded blank are associated with means for activating the thermoplastic adhesive upon the blank as the forming operation is completed. Preferably and as shown, this activation is effected during the completion of the forming operation, and it permits the use of a relatively light forming mechanism and does not extend the time of the cycle of operations.

As herein illustrated, guide means are provided for enabling the successive presentation of the blank held in the hands of the operator to corner-lap-forming, to end-wing-folding and to pressing 30 mechanisms and, embodied in the latter, are electrodes which, when energized from a suitable source, set up a high-frequency electrostatic field passing through the end of the box to activate the thermoplastic adhesive during the pressing operation.

35 As illustrated also, the pressing mechanism comprises an abutment member movable into an interior of the box by power-driven mechanism, an associated pressing member, and means energized in timed relation to the movement of

40 the parts of the pressing mechanism for setting up an electrostatic field through the end of the box at the completion of said inward movement.

In accordance with another feature of the invention, control of the movement of the parts of the pressing mechanism is effected through a trigger operated by contact with the box end as it is brought into a position for treatment by these devices and control of the energization of the activating means is effected automatically by movement of the machine parts.

The various features of the invention will be best understood from a consideration of the following description, taken in connection with the accompanying drawings, in which

Fig. 1 is a front elevation of the machine;
 Fig. 2 is a plan view of the machine;
 Fig. 3 is an end elevation from the left, with parts broken away and in section;

Fig. 4 shows a stack of paper box blanks which have been precoated with adhesive and the coating allowed to dry;

Fig. 5 shows one end of a box blank after being partially folded;

Fig. 6 is an angular view of a box-blank held in the hands of an operator after she has bent down the side-wings and has pushed the end of the blank against the corner-lap-folder;

Fig. 7 is a detail in broken end elevation, with the siding abutment elevated and with pressure and heat being applied to the end of the box as it is positioned by said abutment;

Fig. 8 is a detail in broken front elevation, showing the box-blank being moved into contact with the trigger; and

Fig. 9 is an angular view of one of the pressure members of that machine and having an insulated electrode forming its pressure-applying surface.

The illustrated machine is of the semiautomatic type, by which first one end of a box-part and then the other may be formed. It is of the type shown in Letters Patent of the United States No. 2,186,977, granted January 16, 1940, on an application of Cutler D. Knowlton, and is particularly adapted for use with a blank comprising, as shown herein in Fig. 4, a body-portion 10 and various projections, such as opposite side-wings 12, corner-laps 14 and end-wings 16 having end-wing-extensions 18. Such blanks, when folded as shown in Fig. 5, bring the corner laps together inside the end wing and, when finally formed, the end-wing-extension 18 is bent over the edges of the corner laps and secured to the inner surfaces thereof, as shown in Fig. 7.

The adhesive employed may be a vinyl acetate resin, for example, or any other thermoplastic type which is readily activated in a high-frequency electrostatic field, and it will be understood that the one named is only one of a large number of adhesives of similar characteristics in which, when subjected to such a field, heat is set up in or at the adhesive itself. With such an adhesive, it is found possible to restrict the application to limited areas, comprising single stripes 17 on the corner laps 14, triple stripes 19 on the end wing 16 and a stripe covering the end-wing-extension 18. These latter stripes 19 on the end wing and that on the extension 18 are shown by stippling in Fig. 4, and combine in the shape of a letter E. They all are on one surface of the blank. This affords a saving in adhesive and at the same time gives the desired strength of bond even though the adhesives do not come face to face except where the stripes 17 upon the corner laps contact the stripe upon the end-wing-extension 18. Experience shows that with such an adhesive there is a substantial stiffening of the end of the box, thus rendering it possible to use a slightly lighter grade of paper material while still producing a satisfactory box. An adhesive of this type dries to have a hard, non-tacky surface, and thus makes it easy to stack the blanks as shown in Fig. 4, or to pack them in stacked relation without any tendency for one blank to stick to another.

In using the machine, the operator grasps a blank with the hands and, bending the side-wings substantially into parallelism at right-angles to the body-portion 10, presents the blank, in in-

verted position to a substantially vertical side-wall G with the end-wing and its extension projecting over the wall. The wall G is at the front of the machine, convenient for access by the operator, and has, as illustrated, associated with it a horizontal table T on which the edges of the side-wings 12 rest. The machine is so arranged that the operator, forcing the blank (Fig. 6) into the corner between the guide-wall and table, may present said blank successively to the box-making instrumentalities which are arranged to perform cumulative operations on the blank to complete an end of the box. These instrumentalities comprise a corner-lap-folder A provided by a concave portion of the wall G, a folder or scroll D (Fig. 1) for holding the end-wing to a vertical position, a sliding abutment E for folding the end-wing-extension around the edges of the corner-laps and into contact with the inner surfaces thereof to a position indicated in Fig. 7, whereupon said abutment cooperates with a pressure-applying mechanism F for compressing the parts to complete the end-formation. The direction of presentation of the partially folded blank to the wall-portion A, as indicated by the arrows in Fig. 6, is such that the corner-laps are turned inwardly toward each other by the contact of their ends with the opposite sides of the concave surface, so that at the time when the ends of the side-wings 12, or the junctures between these wings and the corner-laps 14, in travel to the left, contact with the guide-wall G, these corner-laps are in alinement with each other.

This guide-wall G is supported by a bracket 20, which is attached to an arm 22 held by clamp-bolts 24 on the upper ends of a post 26 secured to a base 28 forming part of the frame of the machine. The frame is provided with legs 30 and has a sub-frame 34 (Figs. 2 and 3) mounted on the base 28. Just above the base 28 and extending across the machine is a drive-shaft 36, which receives power through a gear 38 and a pinion 40 from an electric motor 42, indicated by dot-and-dash lines in Fig. 3.

Because the machine may be utilized for boxes of various depths and for forming the ends of covers, the table T is vertically adjustable. It is shown as attached to a socket 109 mounted at the upper end of a rod 110, which is guided in the arm 22 supporting the guide-wall and has threaded engagement at its lower end with a sleeve 111 journaled in the base 28 of the frame and which carries a hand-wheel 112. A reinforcing strip 116 is secured to the lower face of the table along the front edge thereof.

After treatment thus by the corner-lap-folder A, the box-blank is moved to the left, being pressed rearwardly into firm contact with the guide-wall G and rested on the table T. The blank is next subjected to the action of a folding mechanism, such as the scroll D, having a curved surface 160 (Fig. 1) which deflects the end-wing from its horizontal position to a substantially vertical position so that it approaches and contacts with the outside of the alined corner-laps 14. This scroll is adjustably mounted, by a bolt-and-slot-connection 162 (Fig. 2) on the subframe 34. It may thereby be located across the frame in the correct relation to the pressure mechanism F. A finger 164 (Fig. 1), the under edge of which is inclined upwardly to facilitate the admission of the end-wing supported on the upper edge of the guide G, extends rearwardly from the scroll along the path of the

work and serves to overlie the advancing end wing and to retain it from rising above the proper level in entering said scroll. Projecting from the scroll, in the direction of travel of the blank, is a vertical wall 165 (Fig. 1) which holds the end-wing in contact with the corner-laps until it comes under the influence of the pressure mechanism.

After the turning down of the end-wing, progressive movement of the partially folded blank to the left in the hands of the operator brings it into a position (Fig. 8) in front of the pressure-applying mechanism F and directly above the abutment-slide E, this position being determined by contact of a corner 166 (Fig. 6) of the box with a stop 168. This is supported in such an inclined position that it will contact only with the firm, not easily distorted portion of the box and will thus accurately center said box to receive the action of the mechanism which folds in the end-wing-extension and applies pressure to the entire end-formation. Slightly beyond the plane in which lies the point of engagement of the box-corner with stop 168 and below said stop is a vertical gage-surface 169 (Fig. 1). This, receiving contact of the juncture between the sidewing and corner-lap, limits to a very small amount the departure of the partially folded blank from the correct form if the operator allows the side-wing to become displaced outwardly as it arrives at the pressure-applying position.

Movement of the abutment-slide E and the pressure-applying mechanism F is effected by power delivered from the drive-shaft 36 under the control of a clutch 170 (Fig. 1). The loose half of this clutch is attached to a pinion 172 which meshes with a gear 174 mounted on a cam-shaft 176 (Fig. 2) journaled in the subframe 34. The clutch 170, details of the construction of which are not shown herein since it may be of any convenient construction, is so arranged that it imparts a single revolution to the cam-shaft 176 and then is opened. The tripping of this clutch is accomplished through mechanism shown in said Patent No. 2,186,977 under the control of a trigger 180 (Figs. 2 and 3) in the form of a bell-crank-lever and pivotally mounted, with one arm directly in the path of movement of the box (Fig. 8). As the box is brought into operative position with respect to the mechanisms E and F, the other arm of this trigger 180 will bear on a forward crank-portion of a rearwardly extending rod 182 (Fig. 2) and turn said rod to trip the clutch. The first result of movement of the shaft 176 will be to cause a slide 192 of the abutment E to be raised from the position shown in Fig. 3 to the position shown in Fig. 7, thus turning the end-wing-extension 18 up into contact with the inner surfaces of the corner-laps 14. A path-cam 184 (Fig. 3) on the shaft 176 imparts a swinging movement to a lever 186, the upper end of which is provided with a cam-roll 188 coacting with the cam-track and the lower end of which is connected by a link 190, adjustable as to length, with the slide 192. This slide is supported for vertical movement in a guide formed between the subframe 34 and a casting 194 secured thereto. The work-contacting face of the slide is upon a detachable face-plate 196, dimensioned to fit the blank to be treated, which plate is joined to the body of the slide by a dovetail 198 and is held in position by a spring-plunger 200 (Fig. 8). The table T is cut away at 202 (Fig. 2).

to permit the slide to rise above the level of the table. This face-plate 196 is recessed along its lower edge at 204 (Figs. 3 and 9) to receive the upturned end-wing-extension 18 when pressure is applied. It will be noted also that the slide itself has a recess 206 (Fig. 3) to avoid contact with the corner of the pressure-applying mechanism F, as will be clear from Fig. 7. While the device E is in its uppermost position, as shown in Fig. 7, it serves as an abutment to receive pressure applied to the end of the box through the mechanism F which has a horizontally slidable U-shaped or hollow slide member 210 (Fig. 2). This slide member has along its lower edges laterally extending flanges 212 (Fig. 8) which are received beneath overhanging plates 214 bolted to the subframe 34. Associated with this slide 210 is a block 220 closing the rear open end of the U and slidably received therein. This block is provided with a roll 222 contacting with a cam 224 on the shaft 176 and the pressure applied by the cam to the roll 222 is communicated to the slide 210 through a preloaded spring 226 interposed between the block 220 and the forward, closed end of the slide 210. This spring surrounds a stud 228 projecting from the block 220 and extending through an aperture in the forward end of the slide 210, where it receives a retaining nut 230. The degree of preliminary loading of the spring is regulated by a nut 232 threaded on the stud 228. Springs 234 rest against the closed ends of recesses 229 formed in lateral projections 235 from the slide 210. They surround rods 236 passing through the recesses 229 and threaded into an upright portion of the subframe 34 adjacent to the bearings of the cam-shaft, while the forward ends rest against nuts threaded on the rods. These springs hold the roll 222 in contact with the cam 224 and return the slide after it has pressed the end of the box. At the forward end of the slide 210 is provided a face-plate 240, (Figs. 2 and 3), which has a recess 238 to receive the nut 230 and the end of the stud 228 and is attached to the slide 210 by screws 242 held against loosening by set-screws 244. This face-plate is provided along its lower edges with a strip 246 (Fig. 8) supporting the inturned extension of the end-wing. The partially bent-in extension is thus prevented from straightening, so that the slide 192, 196 will surely turn it up and not distort or crush the end of the box heightwise thereof. This strip 246 is beveled, as indicated at 248 in Fig. 8, to avoid any interference with the oncoming edge of the end-wing-extension as the box is moved laterally into pressure-receiving position. After the application of pressure by the cam 224, the springs 234 retract the slide 210, and the slide 192 is again lowered, thereby leaving the box free for removal from the machine.

Since the adhesive coating on the blank is dry, hard and non-tacky, such a forming of the box end would be ineffective were it not for the activation of this adhesive during the application of pressure. Consequently, provision is made for the application of an electrostatic field to the box end during the cycle of the drive shaft 36, first by providing an electrode plate 195 (Fig. 9) which projects slightly beyond the surface of the face plate 196 of the abutment slide 192 and which may be E-shaped. This E-shaped electrode has a slightly relieved portion 204 to receive the end-wing-extension 18 and is insulated from the face plate 196 by insulating material 250, which is here shown as formed from sheets

but which could be a molded plastic insulating material in one piece, if desired, or the whole face plate 196 could be an insulating material, such as the cloth and plastic material known as "Textolite." Second, we have attached to the face plate 240 of the pressure applying mechanism F an electrode plate 241 (Fig. 7) of electrically-conductive material which may be shaped like the E-shaped electrode 195 but which is shown (Fig. 8) as a solid, rectangular plate substantially coextensive with or larger than the boundaries of that electrode. This electrode plate 241 is insulated from the face plate 240 on the slide 210 by means of insulating material 252 and is held in position thereon by screws which are also insulated by bushings 254. Similar bushings 256 are utilized for the screws which hold the E-shaped electrode on the face plate 196 and, associated with one of these latter screws, there is a sliding contact 258 to the fixed portion of which there is attached an electrical lead wire 260 by means of which a high-frequency current may be supplied from a high-frequency oscillator 300. The other side of this oscillator is connected by a lead 262 to the fixed portion of a sliding contact 264 associated with the electrode 241, and it will be understood that power is supplied to the oscillator from an alternating current source connected to the leads 266.

The application of the electrostatic field to the end of the folded box held under light pressure is required for only a brief interval, of the order of one or two seconds. This time is, however, less than the time required for the cycle of operation of the drive shaft 36 and hence of the cam 184 and the cam 224. Accordingly, the energization of the electrodes 195 and 241 is conveniently controlled by means of a switch 278 (Fig. 7) inserted in the plate circuit of the oscillator 300 and supported upon the frame of the machine so that it may be closed by the contact therewith of a cam 272 attached to the side face of the cam 184 (Figs. 2 and 3). The closing of the switch will be effected at a point 274 on the cam where light pressure has been applied by the power-driven mechanism and will be maintained up to a point 276 (Fig. 3) prior to the relief of that pressure. Inasmuch as the heat produced by the field ceases almost immediately with the breaking of the energized circuit, a sufficient time will remain between the opening of the circuit at 276 and the relief of the pressure afforded by the parts E and F so that the adhesive will set and hold the box parts in assembled or completely formed relation. By changing the extent of the cam 272, the time of energization may be controlled.

In preparation for the use of the machine, the box blank is coated in the desired areas with a thermoplastic adhesive, and this is allowed to dry until it becomes hard and non-tacky. Blanks so prepared may be handled freely and packed or stacked as desired. An end of the box is then folded and presented to the machine by grasping the box blank and bending the side wings into substantial parallelism. The operator, holding the partially formed box in inverted position, will then carry the blank endwise inward toward the guide wall G (Fig. 8) to cause the corner laps to be folded in by the curved portion A, with the end wing projecting over the top of the wall. The blank will then be moved to the left, supporting it on the table and guiding it by the engagement of the corners formed between each corner lap and the end of its side

wing as the blank is pressed against the wall G. In its advance, the blank will be treated by the folder or scroll D which turns the end wing through substantially a right angle to the body portion 10. The continuance of this movement results in bringing the downturned end wing into position in front of the pressure-applying mechanism F, where the position of the box will be determined by its engagement with the stops 168 and 169, while the side of said box will engage the trigger 180. The latter trips the clutch 172 and causes the elevation of the abutment slide E to complete the folding of the end wing extension. The succeeding movement of the pressure slide 210 will press the end of the box against the abutment E to set the end formation. At this time, the operation of the cam 272 in closing the switch 278 will energize the electrodes upon the abutment E and the mechanism F and will cause a high-frequency electrostatic field to be passed through the end of the box, activating the adhesive thereon. This activation will be completed prior to the end of the cycle of the operating cam 184 and the plate circuit of the oscillator will be opened by the switch as the latter is released by the cam plate 272 on this operating cam 184. It has been found that a much lighter pressure is adequate where a high-frequency field is employed, so that from 50 to 60 pounds per square inch is all that is needed. With the particular box style which is illustrated, a total pressure of about 600 pounds is sufficient instead of the several thousands pounds which is required when pressure setting is depended upon. As the cycle of the machine is completed, the slides E and F retreat, releasing the box with one end formed and held by the set adhesive.

This application is a continuation-in-part of our application Serial No. 461,144, filed October 7, 1942, which has become abandoned.

Having described our invention, what we claim as new and desire to secure by Letters Patent of the United States is:

1. In a semiautomatic box-end-forming machine, a guide positioned in unobstructed relation to the front of the machine so that the operator may move a partially formed box manually along said guide, box-end-forming means positioned along said guide for performing successive operations upon a blank previously coated with thermoplastic adhesive and advanced by the operator from one means to another, one of said forming means having relatively movable pressers provided with electrode plates, at least one of said pressers being mounted for movement into and out of a partially formed box, rotary power means operating in a cycle to move said movable presser back and forth, connections between said electrodes and a source of high-frequency electric power, said connections including sliding contacts for the movable electrode thereby to pass an electrostatic field through the end of the box to activate the adhesive, a clutch constructed and arranged to control the movement of said movable presser, and a cam switch on said power means included in said connections for energizing said electrodes during said cycle of movement.

2. In a box-end-forming machine, comprising parts movable relatively to one another engaging the inner and outer faces of the end of a partially formed box to which there has been applied a previously dried coating of thermoplastic adhesive, power-operated mechanism for producing said relative movement, electrodes as-

sociated with said relatively movable parts adapted when energized to pass an electrostatic field through the end of the box, a trigger for controlling said power-operated mechanism, said trigger being positioned for actuation by the box as it is brought into engagement by said relatively movable parts, and rotary switch means actuated by said power-operated mechanism for connecting a source of high-frequency electric energy to said electrodes after the engagement of the end of the box by the relatively movable parts and disconnecting said source before said parts disengage the end of the box.
